Fig. 8

FIG. 1 is a top plan view of a package of bottles, showing my new design with the cover omitted;

FIG. 2 is a side elevational view;

FIG. 3 is an end elevational view;

FIG. 4 is a top plan view similar to FIG. 1 but showing a modified form of my new design;

FIG. 5 is another top plan view similar to FIG. 1 but showing still another modified form of my new design;

FIG. 6 is a perspective view of the form shown in FIG. 5 with the cover in place;

FIG. 7 is a perspective view of the form shown in FIG. 4 with the cover in place; and

FIG. 8 is a perspective view of the form shown in FIG. 1 with the cover in place.

The covers have the same appearance as the respective bottom halves and the vertical lines around the center of the containers in FIGS. 6, 7 and 8 indicate the color contrast of a tape holding the cover and bottom portions together.

I claim:

The ornamental design for a package of bottles, substantially as shown and described.
